SPEAKER HOUSING

Ralph M. La Zar, Skokie, and John P. Vanderhoef, Evanston, Ill., assignors to Car Tapes, Inc., a corporation of Illinois

Filed Apr. 24, 1969, Ser. No. 16,886

Term of patent 14 years

Int. Cl. D14—01
U.S. Cl. D26—14

FIGURE 1 is a perspective view of our new design for a speaker housing;

FIGURE 2 is a front elevational view thereof;

FIGURE 3 is a side elevational view thereof;

FIGURE 4 is a fragmentary sectional view taken along line 4—4 of FIGURE 1.

We claim:

The ornamental design for a speaker housing, as shown.
